UNITED STATES PATENT OFFICE.

WILLIAM B. H. DOWSE, OF NEWTON, MASSACHUSETTS.

DESIGN FOR A SOCKET-PIECE FOR BALL-AND-SOCKET FASTENERS.

SPECIFICATION forming part of Design No. 33,854, dated January 8, 1901.

Application filed November 6, 1899. Serial No. 736,049. Term of patent 14 years.

To all whom it may concern:

Be it known that I, WILLIAM B. H. DOWSE, of Newton, in the county of Middlesex and State of Massachusetts, have invented a new and useful Design for a Socket-Piece for a Ball-and-Socket Fastener, of which the following, taken in connection with the accompanying drawings, is a specification.

My invention consists in a design for a socket-piece for a ball-and-socket fastener, of which the following is a specification, reference being had to the accompanying drawings, in which—

Figure 1 is a plan of my socket-piece. Fig. 15 2 is a cross-section of the same, taken on line 2 2 of Fig. 1.

As shown in the drawings, the leading or material feature of my design consists of a number of leaflets A A, forming a part of the 20 socket-piece and surrounding an embossed annular body part B, said embossed portion be-

ing formed of a series of annular rounded or curved faces leading from said leaflets and arranged concentrically and having the appearance of joined circular bands, the outer 25 one being of greater width than the remaining ones, as shown.

Having described my invention, what I claim as new, and desire to secure by Letters Patent, is—

The design for a socket-piece for a ball-and-socket fastener as herein shown and described.

In testimony whereof I have signed my name to this specification, in the presence of 35 two subscribing witnesses, on this 1st day of November, A. D. 1899.

WM. B. H. DOWSE.

Witnesses:

G. W. PHILLIPS,
A. H. FLANNERY.
